UNITED STATES PATENT OFFICE.

OLIVER HOWARD GENTRY, OF OPELOUSAS, LOUISIANA, ASSIGNOR OF ONE-HALF TO JOSEPH BLOCK, OF SAME PLACE.

STEAM-BOILER.

SPECIFICATION forming part of Letters Patent No. 375,282, dated December 20, 1887.

Application filed August 5, 1887. Serial No. 246,211. (No model.)

To all whom it may concern:

Be it known that I, OLIVER HOWARD GENTRY, a citizen of the United States, residing at Opelousas, in the parish of St. Landry and State of Louisiana, have invented a new and useful Improvement in Steam-Boilers, of which which the following is a specification.

My invention relates to an improvement in steam-boilers; and it consists in the peculiar construction and combination of devices, that will be more fully set forth hereinafter, and particularly pointed out in the claim.

In the accompanying drawings, Figure 1 is a vertical longitudinal central sectional view of a steam-boiler embodying my improvements. Fig. 2 is a vertical transverse sectional view of the same, taken on the line $\alpha\alpha$ of Fig. 1. Fig. 3 is an enlarged detail sectional view.

20 A represents a pair of circular drums, of suitable length and diameter, which are provided on their outer sides with openings B and on their inner sides with openings C, which are much larger than the openings B, and are 25 concentric therewith.

D represents a series of horizontal water-tubes of suitable diameter, which have their ends connected to the openings C, and extend from one drum to the other, thereby supporting the drums in a vertical position. The said drums are supported upon a setting of brick-work or masonry, E, of the ordinary construction, and a covering or case, F, extends upward from the wall of this setting and envelops the boiler. In one end of the setting is constructed a combustion-chamber, G, having an ash-pit, H, below it, a grate, I, being arranged between the combustion-chamber and the ash-pit in the usual manner. On the front 40 side of the boiler, and communicating with the openings B in the front boiler, is arranged a smoke-stack, K, which is secured to the drum A and steam-drum O by means of bolts L.

M represents a mud-drum, which is arranged 45 transversely under the lower side of the rear drum, A, and communicates therewith through a short vertical pipe, N.

O represents a steam-drum, which is arranged horizontally over the water-drums and 50 communicates with the upper sides thereof through short vertical pipes P.

The outer sides of the drums A are connected by means of horizontal flues R, the ends of which extend through the openings B, the said flues R extending centrally through the water-tubes D. One end of each of the said flues R is swaged and provided with an annular flange, S, which extends laterally therefrom and bears against the outer side of the front drum, A. The opposite extremities of the flues R are screw-threaded and are extended through the outer side of the rear drum, A, and non-corrosive nuts T are screwed onto the said threaded extremities of the flues and bear against the outer side of the rear drum, and thereby effectually secure the flues thereto. The outer sides of the said nuts are bent over inwardly, so as to form lips U, that cover the ends of flues R and preserve the same from direct contact with the fire. The inner edges 70 of the said lips are flush with the inner sides of the pipe R, to prevent the said lips from obstructing the passage of the products of combustion through the said pipes R.

When the boiler is filled, the water in the drums A and the tubes D entirely surrounds the flues R, which extend through the centers of the said tubes. When a fire is started in the furnace, the smoke, flames, heat, and products of combustion pass upward around the water-tubes and circulate around the same, in the direction indicated by the arrows in Fig. 1, until they reach the rear drum, A, when they deflect, pass under the said rear drum, and then pass forward through the flues R into the stack K, up which they escape.

By providing the drums with the connected water-tubes D, and by providing the flues R, which extend longitudinally through the water-tubes and through the drums A, the boiler is given a maximum amount of heating-surface, and consequently steam can be generated therein with the smallest possible amount of fuel.

The boiler will of course be provided with the usual safety-valve, try-cocks, and water-indicator.

Having thus described my invention, I claim—

In a tubular boiler, the combination of the drums A, the water-tubes D, connecting the same, the flues R, extending longitudinally

through the centers of the water-tubes and through the drums, the mud-drum M, arranged under one of the drums A, communicating therewith and supported on a bridge-wall, the 5 steam-drum O, arranged above the drums A and communicating therewith, and the smoke-stack K, bolted to the outer side of one of the drums A and to one end of the drum O, substantially as described.

In testimony that I claim the foregoing as to my own I have hereto affixed my signature in presence of two witnesses.

OLIVER HOWARD GENTRY.
